(57) **CLAIM**

The ornamental design for an ultrasound therapeutic treatment security key, as shown and described.

DESCRIPTION

FIG. 1 is a right front perspective view of an embodiment of an ultrasound therapeutic treatment security key embodying the new design.

FIG. 2 is a right rear perspective view thereof.

FIG. 3 is a front view thereof.

FIG. 4 is a rear view.

FIG. 5 is a left view.

FIG. 6 is a right view.

FIG. 7 is a top view; and,

FIG. 8 is a bottom view.

Broken lines are used to illustrate features of the ultrasound therapeutic treatment security key which form no part of the claimed design.
